UNITED STATES PATENT OFFICE.

JAMES C. FRENCH, OF MUSKEGON, MICHIGAN, ASSIGNOR TO AUSTIN MACHINERY CORPORATION, OF CHICAGO, ILLINOIS, A CORPORATION OF ILLINOIS.

DUMPING DEVICE FOR CONCRETE MIXERS.

Application filed September 23, 1920. Serial No. 412,331.

To all whom it may concern:

Be it known that I, JAMES C. FRENCH, a citizen of the United States, residing in Muskegon, in the county of Muskegon and 5 State of Michigan, have invented a new and useful Improvement in Dumping Devices for Concrete Mixers, of which the following is a specification.

My invention relates in general to mixing 10 machines for concrete and the like, and more particularly to means for operating and controlling the discharge spout in such a machine.

It has been especially difficult, in the manufacture of machines of this kind, to provide means for controlling the movement of the discharge spout, particularly when the mixer is loaded and in action, due to the weight and shocks of the material against 20 said spout.

It is a principal object of my invention to overcome this difficulty by the provision of power means for moving the spout from closed to discharging position and for automatically locking it in the exact position desired.

Another object of the invention is the provision, in connection with operating means of this character, of a control for 30 positively locking the discharge spout in closed position during the mixing action and preventing accidental, or ill-timed operation thereof.

A further important object of the invention is the provision of means for connecting the operative members of the device with a power mechanism at exactly the desired time to accomplish the results just stated, and means to terminate the action 40 of said members when the automatic locking action takes place.

A still further object of the invention is the provision of a device of the kind described, which is easily operated and sure 45 in action and which is simply constructed, and the parts of which are unlikely to require frequent repair or replacement.

Other objects and advantages of the invention will be apparent as it is better 50 understood from the following description when considered in connection with the accompanying drawing illustrating a preferred embodiment thereof.

Referring to the drawings:

55 Figure 1 is a partially schematic end ele-

vation of a mixer equipped with my invention;

Fig. 2 is a sectional view taken on the line 2—2 in Fig. 1;

Fig. 3 is an enlarged section of the power 60 mechanism by which the device is operated; and

Fig. 4 is an enlarged fragmentary view 65 of the cam locking member showing the means of operation.

In the embodiment of my invention illustrated by the drawings, reference numeral 11 indicates a concrete mixer having its discharging spout 12 shown both in closed position 13 and in discharging position 14. It 70 will be seen that the device is intended to be used with mixing machines of the non-tilting type which require movement of the spout to permit discharging of the contents. The type here shown is a standard cube 75

mixer. Upon the spout is a lever 15 rigidly secured to a rod 16 mounted in a bracket 16' which is attached to the discharge spout, and having a pivotal connection at 17 with a connecting rod 18. This rod has a similar 80 connection at 19 with a crank arm 21 on a shaft 22 of an operating and cam locking member 23.

This member 23 is revolved by means of a gear 24 attached thereto, which meshes 85 with a worm 25 in a bearing 26 retaining the end of a drive shaft 27. The other end 28 of said shaft has a beveled gear 29 loose thereon and constantly turned by a gear 31 operated by the main power mechanism. 90 Slidably keyed to the shaft 27, near the portion thereof on which the beveled gear 29 revolves, is a cone clutch member 32 adapted to be engaged with a companion friction part 33 on said gear when it is desired to 95 move the discharging spout. A pivoted arm 34 is attached to the clutch in such manner that operation of a hand lever 35, which connects with said arm through a connecting rod 36, will cause said clutch to connect with the gear 29, thereby turning the shaft 27 and transmitting power to the member 23. It

will be readily understood, that, instead of using a hand lever for this purpose, means 100 operating automatically upon the completion of a certain number of revolutions of the mixer could be employed.

A rod 37 is connected at 38 to the upper end of the arm 34 and has on its end a roller 39 adapted to fit in recesses 41 in the 110

cam surface 42 of the member 23. Operation of the hand lever 35, or other means of control, not only puts the clutch 33 in mesh, but at the same time withdraws the 5 roller 39 from a recess 41. This permits the member 23 to revolve, thereby moving the discharge spout from closed to discharging position, or vice versa. As this movement is taking place, the roller 39 is pressed 10 against the peripheral surface of said member by a spring 43 having one end attached to the operating lever 35 and the other to a supporting member 44. This spring contact, of course, may be effected in any suitable way, the arrangement just described being merely a convenient illustration. The recesses 41 are situated upon opposite sides of the member 23 so that when one-half of a revolution, which moves the spout from 15 20 one position to the other, is completed the roller 39 drops into one of said recesses. This draws the clutch 33 out of contact with the gear 29, thereby terminating the revolving action of the member 23. The movement of the spout, obviously, is thereby arrested and it is locked firmly in the position which it has then assumed. It will remain so locked until the clutch is again thrown in by operation of the hand lever or 25 30 other control used. In this manner an effective locking device is provided, which will hold the spout in either closed or discharging position so long as desired, and this even though the material in the mixer be in continual action.

It is evident also that the object set forth above, of automatically disconnecting the operative members of the device from the power mechanism and stopping movement 40 of the spout at exactly the point desired, is fully accomplished by the construction just described.

The apparatus may be mounted upon the frame 45 which supports the mixer in any 45 suitable manner to obtain the relation of the parts required for the automatic action previously described.

The effect of my device is to greatly increase the rapidity and accuracy of action 50 of concrete mixing machines of this type, and it is believed that it constitutes a distinct and manifest improvement in the art.

It is thought that the invention and many 55 of its attendant advantages will be understood from the foregoing description, and it will be apparent that various changes may be made in the form, construction and arrangement of the parts without departing from the spirit and scope of the invention or 60 sacrificing all of its material advantages, the form hereinbefore described being merely a preferred embodiment thereof.

I claim:

1. In a mixing machine, the combination 65 of a discharging spout and power operat-

ing means therefor, said means comprising a rotatable operating disk, means operatively connecting said disk with said discharging spout, power driving means, and means for connecting said disk with said driving means to operate the spout.

2. In a mixing machine, the combination of a discharging spout and power operating means therefor, said means comprising a recessed operating disk, means operatively connecting said disk with said discharging spout, means normally locking the disk in a predetermined position, means for disengaging said locking means, power driving mechanism, and means whereby disengagement of said locking means operatively connects said disk with said driving mechanism and throws the spout.

3. In a mixing machine, the combination of a discharging spout and power operating means therefor, said means comprising a normally locked operating member, means operatively connecting said member with said discharging spout, power driving mechanism, and means for simultaneously releasing said operating member and connecting the same with said driving mechanism to operate the spout.

4. In a mixing machine, the combination of a discharging spout and power operating means therefor, said means comprising power driving mechanism, spout operating devices between said spout and said power mechanism and normally disconnected from the latter, and means for connecting said operating devices with said power mechanism for operation of the spout.

5. In a mixing machine, the combination of a discharging spout and power operating means therefor, said means comprising a rotatable operating member, connections between said member and said spout whereby rotation of said member operates the spout, said member being normally inoperative, a source of power, and means for connecting said member with the power when it is desired to operate the discharge spout.

6. In a mixing machine, the combination of a discharging spout and power operating means therefor, said means comprising a recessed disk, operating connections between said disk and the spout, power driving mechanism, and means for operatively connecting said disk with said power mechanism, said last-mentioned means being normally held out of connection with said power mechanism and having a part engaging in a recess of said disk and being movable to disengage the disk and connect the same with said power mechanism for operation of the spout.

7. In a mixing machine, the combination of a discharging spout and power operating means therefor, said means comprising a recessed disk, operating connections be-

tween said disk and the spout, power driving mechanism, and means for operatively connecting said disk with said power mechanism, said last-mentioned means being normally held out of connection with said power mechanism and having a part engaging in a recess of said disk and being movable to disengage the disk and connect the same with said power mechanism for operation of the spout, said recess engaging part being spring-held against the periphery of said disk and adapted upon entering the recess, to disconnect said power mechanism.

15 8. In a mixing machine, the combination of a discharging spout and power operating means therefor, said means comprising a rotatable operating member, means operatively connecting said member with said spout, power driving mechanism, means for operatively connecting said member with said mechanism for operation of the spout, said means being automatically operable to disconnect said operating member from said power mechanism upon completion of the movement of the spout.

9. In a mixing machine, the combination of a discharging spout and power operating means therefor, said means comprising a rotatable operating member, means for operatively connecting said member with said power driving mechanism, means for operatively connecting said member with said mechanism for operation of the spout, and means controlled by the rotation of said member for disconnecting it from said power mechanism.

10. In a mixing machine, the combination of a spout and operating means therefor, said means comprising an operating and control member, means operatively connecting said member with said spout, driving mechanism, and means for connecting said member and said mechanism and for disconnecting said parts after predetermined movement of the spout.

11. In a mixing machine, the combination of a discharge spout, power means for operating said spout, means for operatively connecting the spout to said power means and

for automatically disconnecting it after predetermined movement thereof.

12. In a mixing machine, the combination of a discharge spout, a source of power for operating said spout, manually operated means for connecting said spout to said source of power for operation thereof, and means for automatically controlling said last-mentioned means to disconnect the spout from said source of power upon predetermined movement thereof.

13. In a mixing machine, the combination of a discharge spout, a rotatable operating disk having recesses in the periphery thereof, means for operatively connecting said disk with said spout, power driving mechanism, a driving connection between said disk and said mechanism, clutch mechanism for connecting said driving connection with said power mechanism, and means spring-held against the periphery of said disk and adapted to enter a recess therein to open said clutch mechanism.

14. In a mixing machine, the combination of a discharge spout, a rotatable operating disk having recesses in the periphery thereof, means for operatively connecting said disk with said spout, power driving mechanism, a driving connection between said disk and said mechanism, clutch mechanism for connecting said driving connection with said power mechanism, means for closing said clutch mechanism to operate the spout, and means connected with said clutch mechanism and engaging the periphery of the disk for entering a recess of said disk after predetermined rotation thereof and automatically opening said clutch.

15. In a mixing machine, the combination of a discharge spout, a source of power, an operating disk, means for connecting said disk with said spout whereby rotation of the disk operates the spout, clutch mechanism for connecting said disk with said source of power, and means controlled by the rotation of said disk for disconnecting said clutch mechanism upon predetermined movement of the spout.

JAMES C. FRENCH.
